Primary Examiner—Brian N Vinson*(74) Attorney, Agent, or Firm*—Boyle Fredrickson, S.C.(57) **CLAIM**

The ornamental design of a weapon cabinet, as shown and described.

DESCRIPTION

FIG. 1 is an isometric view of a weapons cabinet incorporating our new design, wherein the phantom lines illustrate environment and form no part of the claimed design;

FIG. 2 is a front elevation view thereof;

FIG. 3 is a right side elevation view thereof, the left side elevation view being a mirror image;

FIG. 4 is a rear elevation view thereof;

FIG. 5 is an isometric view of a second embodiment of a weapons cabinet incorporating our new design, wherein the phantom lines illustrate environment and form no part of the claimed design;

FIG. 6 is a front elevation view thereof;

FIG. 7 is a right side elevation view thereof, the left side elevation view being a mirror image; and,

FIG. 8 is a rear elevation view thereof.
